 Wanderer-Werke vorm. Winklhofer & Jaenicke
 Akt.-Ges., Siegmar-Schonau, Germany

Application December 23, 1937, Serial No. 181,440
 In Germany March 6, 1935

2 Claims. (Cl. 235—60)

The present application is a continuation-in-part of applicant's application Serial No. 66,952, filed March 3, 1936.

The present invention relates to a calculating machine in which correct positive totals can be taken when an adding subtracting totalizer contains a positive amount and is in addition position, and correct negative totals can be taken when the totalizer contains a negative amount and is in subtraction position, the fugitive 1 being automatically taken care of.

The object of the invention is to provide manually or automatically settable means for conditioning the calculating machine for a total-taking operation, by setting of which means an idle stroke of the machine is automatically initiated for shifting the totalizer from its adding position to its subtracting position or vice versa in such cases in which the content of the totalizer corresponds not with the position of the totalizer, immediately after the idle stroke the taking of the correct positive or negative total being automatically performed.

According to the invention this is achieved by means substantially comprising a setting means for total-taking which is provided not only with means for connecting the motor drive to shift the totalizer to position for the kind of calculation corresponding to the character of the amount therein, but also with connections to control devices which are releasable at the end of the change-over operation of the machine, and by means of which connections the motor drive is automatically connected to clear the amount in the shifted totalizer, for a further machine operation.

Mechanism for a calculating machine embodying the present invention is illustrated by way of example in the accompanying drawings, in which:

Figure 1 is a side view of a bookkeeping calculating machine, with the casing removed.

Fig. 1a is a top view partly in section of the right-hand elements of Fig. 1.

Fig. 1b is a perspective view of the left-hand elements of Fig. 1.

Fig. 1c is a side elevation of the differential mechanism for actuating the totalizer.

Fig. 1d is a side elevation showing the control armature with the total key depressed.

Figs. 2-5 are side views illustrating a detail mechanism in different operative positions.

Figs. 6 and 7 are partial side elevations in which various control members, not shown in Fig. 1, are indicated.

Fig. 8 is a side view of a skip device for jumping over printing spaces.

Fig. 9 is a side view showing various motor keys with their corresponding operating connections.

Fig. 10 is a side view showing the mechanism for shifting the totalizer to addition or subtraction position.

Fig. 10a is a side view of a detail showing the connection of the shift member with the subtraction key according to Fig. 10.

Figs. 11 and 12 are end views of a detail showing the shift member for the subtraction slide according to Fig. 10 in two different positions.

15 Figs. 13 and 14 are end views of a detail showing the subtraction slide according to Figs. 7 and 10 in different positions.

Figs. 15 and 16 are end views of a detail showing the shift slide actuated by the subtraction 20 slide, for the totalizer of Figs. 1, 7, 10 in different positions.

Fig. 17 is a perspective partial view of the totalizer and shift mechanism seen from the rear.

Fig. 18 is a view similar to Fig. 17 of the totalizer and engaging means.

Fig. 19 is a perspective partial view of the tens carrying mechanism.

Figs. 20 and 21 are sections through the tens carrying mechanism taken on line 20—20 of Fig. 30 19 and showing two different positions.

Figs. 22, 23 and 24 are sections through the tens carrying mechanism taken on line 22—22 of Fig. 19 and showing three different positions.

Fig. 25 is a side view partly in section showing 35 the mechanism for releasing the paper carriage according to Fig. 9.

Fig. 26 is a side view partly in section showing the mechanism for testing the sign of the totalizer content.

40 Fig. 27 is a plan view of the mechanism of Fig. 26.

Fig. 28 is a section through the drive coupling taken on line 28—28 of Fig. 29.

Fig. 29 is a section through the drive coupling taken on line 29—29 of Fig. 28.

Fig. 30 is a side elevation of the mechanism for engaging the motor and coupling.

Fig. 31 is a partial view of the engaging mechanism of Fig. 30.

50 Fig. 32 is a detail view showing the engaging mechanism of Fig. 30.

The drawings illustrate a bookkeeping calculating machine in which the invention is exemplified. There are described and illustrated only 55 the operative parts of a single totalizer 31, al-

though the machine may have a plurality of totalizers and a corresponding multiple of the operating parts hereinafter described. The machine shown in the drawings is of the full keyboard type with digit keys 450 which are held in depressed position, during the operation of the machine, by means of locking bars 451, in the usual manner. By the depression of the digit keys 450 there is effected movement of zero levers 452 whereby these release their associated step bars 453.

Rack sectors 3 are connected by pins 650 to the step bars 453, Fig. 1c, which sectors are freely rotatable on a common shaft 651. Each sector has an arm with teeth 174 engaging teeth 175 of rack bars 173. The rack bars are guided by means of pins 652, 653 engaging slots 176, 177 in the bars and are moved to and fro corresponding to the movement of the rack sectors 3. Accumulators, not shown, can be brought into engagement with the rack bars 173. Springs 654 attached to the rack sectors 3 urge the latter to rock in counter-clockwise direction. Type carriers 16 are jointed to the sectors 3, and by means of a bail 655 resting on the sectors 3, the latter are held in the position shown in Fig. 1c. The bail 655 is carried by a two-armed lever 656 pivoted about the shaft 651, on the left-hand arm of which lever is mounted a roller 657 which cooperates with a cam 658 fast on the main drive shaft 1.

The adding and subtracting totalizer 317 is mounted in a frame 756 supported in a second frame 660 having a rocker arm 757 which is shown in Fig. 1c. The frame 660 rocks about an axis 761 and the rocking of said frame causes the upper or the lower numeral wheel series of the totalizer 317 to come into and out of mesh with the rack sector teeth, as will be hereinafter described. The frame 660 is rocked by means of a disc 763 having a curved cam slot 762 co-operating with a stud 755 on the frame 660. The disc 763 is fast on a shaft 764.

At the beginning of a machine operation the main drive shaft 1 rotates counter-clockwise whereby the cam 658 releases the roller 657, Fig. 1c. Since in those ordinal places in which amount keys 450 are actuated the zero levers 452 have released the corresponding step bars 453, these bars can move to the left (Fig. 1c) under the pull of the springs 654 acting through the sectors 3, this movement being limited by the stems of the depressed amount keys 450. Hereby the corresponding rack sectors are raised by amounts corresponding to the digits of the depressed keys and by means of hammers not shown, the set up digits are caused to be printed by the type carriers 16, at the platen roller 14.

At the beginning of the return stroke of the machine operation in which the main shaft 1 moves contrary to the direction of the arrow 143, the totalizer 317 is brought into mesh with the rack sectors 3 and in the course of the return stroke the set up digit values are entered in the totalizer 317. The introduction of the digit values for addition and subtraction takes place in similar manner, according to whether the upper or the lower series of numeral wheels of the totalizer, by means of a control device hereinafter described, engage the rack sectors 3.

Total-taking from the totalizer is prepared by means of total key 454 and sub-total key 455.

The total key 454 and the sub-total key 455 cooperate at all times with a bell-crank 456 which

is jointedly connected by a pin 457 to a push rod 458. At the right-hand end of the push rod 458 there is jointed a lever 460 pivoted at 459, which lever engages a pin 461 on a rod 462. The rod 462 is connected by a pin 463 with the lower arm of a bell-crank 464 pivoted at 654. At its left-hand end the rod 462 has a slot 466 in which engages a pin 467 on a lever 468. The lever 468 can rock on a pivot 469 and is drawn against the right-hand end of the slot 466 by means of a spring 470 attached to the rod 462. On depressing one of the total keys 454 or 455, the bell-crank 456 rocks in the clockwise direction and through the parts 458, 460 it pushes the rod 462 to the right, in Fig. 1. A pawl 472 pivoted on a pin 471 of the rod 462 is thereby carried to the right. This pawl 472 in this movement engages below a pin 473 on a lever 474 and thereby shifts a rod 475 which engages the motor drive to effect a machine operation, as will now be described. On the other end of the shaft 475 is attached a pawl 665 (Fig. 30) urged in clockwise direction by a spring 667. In position of rest of the machine the pawl 665 is held by the spring 667 in engagement with a square pin 668 arranged on a rod 669 which, as shown in Fig. 31, is jointed at 670 to a lever 671 having several arms and pivoted about a shaft 672. To the lower arm of the lever 671 is attached a spring 673 which tends to turn the lever counter-clockwise. The left arm of the lever 671 carries a pin 674. On the shaft 672 is rotatably mounted a two armed lever 675 (Fig. 30) the left arm of which co-operates with a yoke 579 rotatable about a shaft 676. The right arm of the lever 675 has a lug 677 (Fig. 32) cooperating with a stop 678 on a yoke 679. The yoke 679 is rotatably mounted on a shaft 680. The yoke 679 has a lower arm 681 and an upper arm 682 the former of which arms has a pawl 684 pivoted on a pin 683 and urged in counter-clockwise direction by a spring 685, while the upper arm 682 is connected at 686 to a link 687 (Fig. 32) which link is jointed at 688 to a lever 690 (Figs. 30 and 31) pivoted about a pin 689 (Fig. 31). The lever 690 has also jointed thereto a stop rod 692 (Fig. 29). This stop rod 692 extends into the casing 693 of the drive coupling. At the right end of the rod 692, Fig. 29, lies a pawl 694 which is mounted on the driven part of the coupling 695, Fig. 28. A spring 696 (Fig. 29) tends to turn the pawl counter-clockwise. The driving part 699 of the coupling 695 is rotatably mounted on a shaft 711. The pawl 694 is connected to a pin 697 having a semi-circular portion (Fig. 28) co-operating with corresponding notches 698 in the driving part 699 of the coupling. This driving part 699 has external teeth 700 engaging a worm pinion 701 mounted on a shaft 702 which is connected through a resilient coupling 703 with a motor 704 (Fig. 30) for driving the machine. On a stub end 705 of the shaft 711 (Fig. 28) is fixed an arm 706 (Fig. 30) connected by a pin 707 to a thrust rod 708. The thrust rod 708 is connected to an arm 710 by means of a joint pin 709, which arm is fixed to the main drive shaft 1. The said shaft also carries a further arm 712 (Fig. 30) having a pin 713.

A rock lever 714 (Fig. 30) is also connected at 688 to the link 687, which lever has a projection 715, and at its right hand end bears against a lug 716 on the arm 706. The projection 715 co-operates with a roller 717 attached to a lever 719 pivoted at 718. The lower end of the lever 719

carries a contact 720 co-operating with a contact 721 on the machine frame in such a manner that when the two contacts engage the current for starting the motor 704 is switched on, in a manner not shown. A spring 722 urges the contacts 720, 721 towards each other.

If the shaft 478 is rocked counter-clockwise by means of the lever 474 and rod 462 (Fig. 1) to engage the motor drive, the pawl 684 (Fig. 30), releases the square pin 688 and the rod 689 under the action of the spring 673, moves to the left, (Fig. 31) due to the turning of the lever 671. On counter-clockwise turning of the lever 671 the two armed lever 675, by means of the pin 674, is also turned counter-clockwise so that its projection 677 (Fig. 32), releases the arm 678 of the yoke 679. By the action of a spring 723 the yoke 679 is given a counter-clockwise movement which causes the upper arm 682 of the yoke 679 to move the link 687 to the left in Figs. 30 and 31. The link 687 then rocks the lever 690 counter-clockwise whereby the stop rod 692 is moved to the left (Fig. 29) and the pawl 694 released. By the counter-clockwise movement of the lever 690 the lever 714 is moved to the left (Fig. 30) and its projection 715 releases the roller 717 of the lever 719. Under the action of the spring 722 the lever 719 can move counter-clockwise to close the contacts 720, 721 and start the motor.

Owing to the turning of the pawl 694 in counter-clockwise direction, the semi-circular pin 697 is similarly rotated so that it comes into co-operation with one of the notches 698 of the driving member 699 of the coupling, whereby this member and the driven member 695 are coupled. When the motor 704 begins to rotate in counter-clockwise direction due to closure of the contacts 720, 721, the driving member of the coupling is set in rotation through the elastic coupling 703, shaft 702 and worm 701. The driven coupling member participates in this rotation due to its connection by means of the pin 697, and the shaft 711 connected to said member also rotates anti-clockwise. The shaft 711, by means of the arm 706 imparts a reciprocatory movement to the connecting rod 708 whereby, through the arm 710 the main shaft 1, during the first half of a rotation of the shaft 711, moves in counter-clockwise direction and during the second half of said rotation, said main shaft moves in clockwise direction back to the position shown in Fig. 30. The arm 712 fast on said shaft 1 (Fig. 30), brings its pin 713 into contact with the pawl on the lower arm 681 of the yoke 679 (Fig. 32), during the movement of the main drive shaft 1 in counter-clockwise direction. The pawl 684 is thereby turned clockwise against the action of its spring 685 but without the yoke 679 being moved from its coupling engaging position. After the pin 713 of the arm 712 has moved past, the pawl 684 snaps back into the position shown in Fig. 32. At the beginning of the clockwise turning of the main drive shaft 1, that is, during the second half of a rotation of the shaft 711 the pin 713 of the arm 712 moves upwardly against the pawl 684 and, as the pawl 684 cannot yield, its further movement shifts the yoke 679 clockwise back to the position of Fig. 30. Due to the clockwise movement of the yoke 679, the upper arm 682 causes the link 687 and the stop rod 692 to return to the right as in Fig. 29, so that the rod 692 assumes this right-hand position. After a complete rotation of the driving member 699 of the coupling the pawl 694 strikes

the stop rod 692 which produces shifting of the pawl 694 in clockwise direction against the action of the spring 696. The pin 697 is thereby also shifted in clockwise direction out of co-operation with the coupling driving member 699, and the driving and driven members are no longer coupled. The rotation of the shaft 711 is limited to an exact single turn, and consequently the main drive shaft 1 effects an exactly determined to and fro movement.

Simultaneously with the right hand movement of the rod 687 the lever 714 jointed thereto also moves to the right so that its projection 715 returns into co-operation with the roller 717 of the contact lever 719. As long as the shaft 711 has not completed a full turn, the projection 715 and the lever 714, due to the action of the spring, moves over the roller 717 in counter-clockwise direction. The motor 704 thus remains switched on during one complete revolution although the lever 714 and the projection 715 are already in co-operation with the roller 717. Shortly before the shaft 711 has completed a full turn, the right end of the lever 714 is engaged by the projection 716 on the arm 706 and said lever turned clockwise into the position shown in Fig. 30. Clockwise movement of the lever 719 thus takes place against the action of the spring 722, opening the contacts 720, 721 and breaking the motor circuit.

The totalizer 317 has two series of gear wheels 150, 751 engaged with each other, Figs. 17, 18. The gears 150, 751 are rotatable on shafts 752, 753 mounted in a frame 756 pivotable about pins 754, 755, which pins are fixed in rocker arms 757, 758 of the frame 660. The frame 660 and its rocker arms 757, 758 is mounted loosely on a shaft 761 supported in walls 490, 769 of the machine. The extended pin 755 engages a curved slot 762 in a disc 763. The disc is fixedly mounted on a shaft 764 supported by the side walls 490, 769. The arms 757, 758 are connected by a brace 765.

On the counter-clockwise turning of the shaft 764, Fig. 18, the curved slot 762 causes the arms 758, 757 to rock counter-clockwise whereby the gears 751 engage the rack sectors 3. The gears 150, 751 have tens carrying lugs 766, 768 co-operating with carry preparing levers 770, 771. The levers 770 are supported on a common shaft 772 and the levers 771 on a common shaft 774. The shafts 772, 774 are fixed in the rocker arms 758, 757 and also serve to brace said arms. Each carry preparing lever 771 has an upper extension 775 bearing against the carry preparing lever 770 of the same ordinal places, Fig. 20, and a spring 776 holds the lower arm of the carry preparing lever 771 in contact with the shaft 761. Arms 777 of the levers 771 bears against fork levers 778 rockably mounted on a common shaft 779 supported by side walls 780, 781, Fig. 19. These side walls are fixed on two shafts 782, 800 supported by the side walls 490, 769 of the machine. The levers 778 are urged by springs 783 in clockwise direction to hold them against bends 784 of the tens carrying slides 785, Figs. 19, 20, 21, which slides are guided by means of notches in webs 786, 793, slots 787 and pins 788, and a shaft 789, Fig. 21. The tens carrying slides carry two groups of teeth 790, 791. Springs 792 urge the slides downwardly, Fig. 21. The gears 150, 751 only engage the slides when the accumulator is disengaged from the rack sectors 3, Figs. 17, 20, 22. Each tens carrying slide 785 has an extension

794 with a lug co-operating with a yoke 795, which yoke with its shaft 796 is supported in the side walls 780, 781, and is held by a spring 797 against the extensions 794 of the slides 785. The yoke 795 has a bend 798 at its left hand end, Fig. 19, co-operating with a lug 799 of the rocker arm 758, Figs. 18, 19. On a shaft 801 is mounted a yoke 802 the left end of which in Figs. 18, 19 has two arms 803, 804 and in the arm 803 is mounted a shaft 806 serving to restore the tens carrying slides 785. Owing to the weight of the shaft 806 the yoke 802 is rocked counter-clockwise to such an extent that the arm 803 bears against the shaft 761. The arm 804 has a pin 805 co-operating with a heel 807 on the cam disc 763, Fig. 18.

Upon engaging the totalizer 317 with the rack sectors 3 from the position shown in Fig. 20 to the position shown in Fig. 21, the carry preparing levers 770, 771 remain in the region of action 20 of the tens carrying lugs 766, 768, Fig. 23. If during setting up of the digits in the numeral wheels of the totalizer 317 by means of the rack sectors 3, the value 9 is exceeded in an order, then the tens carrying lug 766, Fig. 23, strikes a 25 nose on the tens carrying lever 770 and rocks said lever in clockwise direction, Fig. 23. The lever 770 carries with it the carry preparing lever 771 bearing against it, which lever 771 rocks in counter-clockwise direction against the action 30 of the spring 776. The arm 771 of the carry preparing lever 771 which bears against the forked lever 778 in both the engaged and disengaged condition of the totalizer 317, rotates the forked lever 778 during the rocking of the lever 771, against the action of the spring 783 and in the clockwise direction Fig. 23. During this rotation of the forked lever 778, a shoulder 35 808, Fig. 23, of said lever releases the bend 784 of the tens carrying slide 785 in the next higher order, so that the corresponding tens carrying slide 785 can move downwardly under the action of its spring 792 until the lug of its extension 794 bears against the yoke 795, Fig. 23, with resulting preparation of the tens carry to be effected. The actual tens carry does not take place until the totalizer 317 is disengaged from the rack sector 3, and has come into engagement with the tens carrying slide 785, as shown in Fig. 22. On disengagement of the totalizer from the rack sectors 3 and its engagement with the tens carrying slides 785, the lug 799 of the rock lever 758, Figs. 18, 19, 24, encounters the bend 798 of the yoke 795, Fig. 24. Hereby the yoke 795 is shifted against the action of its spring 797, in clockwise direction, Fig. 24, as a result of which all the tens carrying slides 785 are released. Those tens carrying slides 785 which have been prepared for a tens carry by shifting of the forked lever 778 as in Fig. 23, then effect the tens carrying step under the action of their springs 792, such step being limited by the striking of their lower edges on the shaft 806, Fig. 24. Hereby tens are carried into the next higher orders.

In engaging the totalizer 317 for setting up a further amount during the next machine operation, the heel 807 of the cam disk 763 strikes against the pin 805 on the arm 804 of the yoke 802, Fig. 18, imparting to such yoke a rocking movement in counter-clockwise direction, Fig. 24, during which the shaft 806 fixed in the yoke 802 returns the released tens carrying slides 785 from the position of Fig. 24 back into the position of Fig. 20, whereby the tens carrying slides 75

785 are restored to their normal position and the tens carrying mechanism is ready for further operation.

As shown in Fig. 19, the highest order and the 5 lowest order of the totalizer 317 each has a special forked lever 810, 811. The forked lever 810 of the lowest order and the forked lever 811 of the highest order are connected to each other by a yoke 812. The forked lever 811 controls an additional tens carrying slide 813 cooperating with gears 814, 815, Fig. 17, which gears serve to test or determine the sign of the totalizer content as will be hereinafter described. The forked lever 810 in the lowest order controls the tens carrying slide 785 which cooperates with the gears of the lowest order. The forked lever 810 is moved only by the forked lever 811 and therefore by the tens carrying lugs 766, 768 of the highest order. If the numeral wheels of the highest order of the totalizer pass through zero then a unit is introduced automatically by means of the yoke 812, into the lowest order. This device serves for taking true negative totals. Preferably there is provided in the totalizer 317 an additional order and tens carrying device beyond the number of rack sectors and rows of digit keys 450 that are present, in order that, if the capacity of the totalizer should be exceeded, the sign of its content will remain unchanged and introduction of the fugitive 1 into the lowest order by means of the yoke 812 will be prevented, with actuation of the device hereinafter described for indicating the sign of the totalizer content. The mechanism for introducing the unit into the lowest order operates moreover in practice only when the sign of the totalizer content changes. The capacity of the orders of the totalizer which are actuated by rack sectors 3, would have to be exceeded ten times before the extra order of the totalizer 317, which is not actuated by a rack sector 3, would introduce a fugitive 1 into the lowest order.

As described in the foregoing the totalizer 317 is rocked counter-clockwise by means of the cam disk 763 about the axis 761, Fig. 1c, and thereby engages the rack sector 3. The totalizer 317 and the means for conditioning this accumulator for addition or subtraction, are arranged in the same manner as described in the Ewald application Serial No. 39,065, filed September 3, 1935. The right-hand side wall of the frame 756, Fig. 17, carries two pins 322, 323, and the arm 757 carries two pins 851 and 852. On the pins 851 and 852 there is mounted a slide 324 having a slot 854 in which engage the pins 851, 852. Washers 855, 856 hold the slide 324 on the pins 851, 852. The slide 324 has two cam lugs 478, 476 spaced by a gap 900, the pins 322, 323 of the totalizer frame 756 cooperating said lugs and gap.

When the totalizer 317 is in the addition position the pin 322 lies against the lug 476 and the pin 323 is in the gap 900. At its lower end the slide 324 has a pin 479 engaging a forked lever 480, Fig. 17, which is fixed by means of a bolt 481, Fig. 1, to a lever 482. A pin 483 at the upper end of the lever 482 cooperates with a bell-crank 485 pivoted at 484, the right-hand arm of which bell-crank engages a hole 486 in a slide 487, Fig. 18. As shown in Figs. 1 to 5, the slide 487 has slots 488 with which engage pins 489 carried by brackets 491, 492, fixed to the side wall 490. The slide 324 has a slot 857, Fig. 17, engaging a pin 858 fixed on a slide 339, said slide having a slot 860 engaging a pin 861 on the side wall 769. A shaft 862 is fixed in the side walls 490, 769 and a

two-armed lever 343 is mounted on said shaft, said lever having two pins 346, 350. The pin 346 can be brought into the path of a shoulder 345 of the slide 339, Fig. 17, as subsequently described. The two-armed lever 343 is connected by means of a yoke 363 to a rotatable arm 556 mounted on the left-hand end of the shaft 362, Fig. 18. On the arm 556 there is jointed at 364 a rod 557 having a hooked end 552, Fig. 7, which lies in the path of a pin 140 on a drive disk 142 fixed on the main drive shaft 1.

When the hook 552 during the forward stroke of the machine drive is carried along with the movement of the pin 140 in the direction of the arrow 143, the arm 556 and the yoke 363 cause a rocking of the lever 343 in clockwise direction.

The slide 339 has a slot 365 into which extends a pin 366 fixed on a lever 367 having several arms. The lever 367 is rotatably mounted on a pin 368 fixed in the side wall 769, and it has two worked ends 369, 370 cooperating with two pins 371 and 372 fixed to a disk 373. This disk 373 is connected by means of a yoke 374, with an arm 375, the disk 373 and the arm 375 being supported by a shaft 376. A rod 326 is jointed to the arm 375 by means of a pin 327 and the rod 326 is connected to a bell-crank 325 (Fig. 10) which cooperates with a subtraction key 554. A spring 325 acts on the rod 326 tending to draw it to the right, Fig. 1. The position shown in Figs. 17 and 18 of the means for changing the nature of calculation, corresponds to the addition position of the numeral wheels 750, 751 of the totalizer 317. If the totalizer 317 is to be shifted over to subtraction, then before the beginning of the machine operation, the subtraction key 554 is depressed. Hereby the arm 375, by means of the bell-crank 325 and rod 326 is turned in clockwise direction as shown in Fig. 10a which produces a clockwise shifting of the disk 373 as shown in Fig. 17. During this movement of the disk 373 the pins 371, 372 move from the position of Fig. 11 into that of Fig. 12, whereby the forked lever 367 is rocked counter-clockwise. During this rocking of the forked lever 367, its pin 366 rocks the slide 339 forwardly about the pin 361 as seen in Fig. 17, whereby a ramp 341 on the slide 339 comes into the region of operation of the pin 359 of the lever 343, Fig. 14. As already described, during the forward stroke of the machine drive, there is effected by means of the drive disk 142, on the main driving shaft 1, a left-hand movement of the rod 557, Fig. 7, and through the arm 556 and the yoke 363, the lever 343 is caused to turn in clockwise direction. Hereby the pin 359 forces the slide 339 downwardly, Fig. 14, and during this downward movement the pin 359 carries also the slide 324 downwardly, said slide being guided on the pins 351, 352. The pin 322 of the totalizer frame 750 is thereby caused to slide from the lug 476 into the gap 360, and the pin 323 out of the gap 360 onto the lug 478, Fig. 14. This produces a shifting of the totalizer frame 750 in clockwise direction about the shaft 754, so that upon engagement of the totalizer 317 with the rack sectors 3, the upper series of wheels 750 comes into mesh with the said sectors and the totalizer 317 is conditioned for subtraction.

Restoration of the totalizer 317 to addition takes place in similar manner. The spring 325, Figs. 1, 18, pulls the rod 326 to the right in Fig. 1 as soon as the subtraction key 554 is released, whereby the arm 375 and the disk 373 by means of the yoke 374 receive a counter-clockwise movement so that the forked lever 367 is shifted by 75

means of the pins 371, 372 from the position of Fig. 12 into that of Fig. 11. The pin 366 of the forked lever 367 then shifts the slide 339 to the left into the position of Fig. 13 so that the shoulder 345 comes into the path of movement of the pin 346 of the two-armed lever 343. If the lever 343 during the forward stroke of the machine drive according to arrow 141 effects a rocking movement in clockwise direction, then the pin 346 lifts the slide 339 to its upper position. By means of the lugs 475, 476, the totalizer is thus shifted into the addition position shown in Fig. 16.

The movement of the slide 324 also serves to determine the nature of calculation.

During the downward movement of the shift slide 324 the pin 479 carries the lever 480 downwardly and rocks the bell-crank 485 (Fig. 1) in such a manner that the slide 487 guided by the slots 488 reaches its upper position. The slide 487 thus always occupies this upper position when the totalizer 317 is set for subtraction, while the lower position of the slide 487 as shown in Fig. 1 always corresponds to the illustrated addition position of the totalizer. The slide 487 can therefore be used for indicating and detecting whether the totalizer is set for addition or subtraction.

When the amount contained in the totalizer is of positive character, that is, when the numeral wheels of the totalizer indicate an amount greater than zero, a rod 416, Fig. 1, extends its front end out of an opening 493 in the side wall 490, to a greater extent than is the case when the amount in the totalizer is of negative character, that is, when the totalizer indicates an amount which is less than zero. The movement of the rod 416 automatically takes place in known manner in dependency upon the sign of the totalizer contents. Many different mechanism for this purpose are known, as for example U. S. Patent No. 1,957,501. According to Figs. 18, 26 and 27, there is mounted on the shafts 752, 753 of the totalizer 317, alongside the numeral wheels of the highest order, the previously mentioned additional pair of wheels 814, 815. The pair of wheels 814, 815 is operated by the highest order wheels with the aid of the tens carrying slide 813, Fig. 19, when the highest order wheels of the totalizer 317 turn through zero. On the right-hand side wall of the frame 756 which rocks about the shaft 754, there is mounted a pin 810 which engages in the lower wheel 815 at a place at which one tooth is cut away. The pin 810 thus permits only one movement of the pair of wheels 814, 815, of the magnitude of one tooth pitch forwards or backwards. On the wheels 814, 815 are fixed lateral tens carrying lugs 811, 812 lying opposite noses 813, 814, of actuating pawls 815, 816. The upper pawl 815 is rotatably mounted on the shaft 772 and has its upwardly extending arm 817 bearing against a bell-crank 818, Figs. 17, 26, which bell-crank is mounted at 919 on a bend 920 of the totalizer rocker arm 757. The rod 416 is pivoted to the bell-crank 818. The rod 416 is jointed at its other end by means of a pin 494 to an arm 428 (Fig. 1a) of a yoke pivoted about a rod 423, which rod is journalized in a block 488 attached to the side wall 490. A further lever 418 is connected to the pin 494. This lever is pivoted on a pin 419 (Fig. 1) in a block fixed to the side wall 490, and has a bend 420 at its left-hand end. The bend is marked with a plus symbol and a minus symbol, and the symbol corresponding to the totalizer amount at any time

is always visible through an opening provided for this purpose in the machine casing.

The setting of the totalizer 317 shown in Figs. 17, 18 corresponds to the addition setting. The position of the tens carrying lug 911 of the upper wheel 814 below the nose 913 of the actuating pawl 915 corresponds to a positive totalizer content.

If the totalizer 317 is conditioned for subtraction by means of the key 554, then as already described the totalizer frame 756 is rocked about its axis 754 by the lugs 478, 476 without the wheels 814, 815 being moved about their axes 752, 753. Only when an amount is being subtracted which is greater than the amount in the totalizer does there take place a shift in the highest order since the numeral wheels pass through zero. The wheel 815 hereby is advanced one step by means of the tens carrying slide 813, Fig. 19, in the manner already described, from the adjacent highest order of the totalizer. The tens carry lug 912, which in the subtraction condition of the totalizer with positive accumulator content, is located somewhat above the nose 914 of the pawl 916, forces the pawl 916 to the right in Fig. 26, as soon as the totalizer content becomes negative. In its shift to the right in Fig. 26, about the axis 774, the pawl 916 carries the pawl 915 along with it at its contact surface, which pawl 915 in turn rocks the bell-crank 918 in counter-clockwise direction as viewed in Fig. 27 against the action of a spring 930, Figs. 18, 27. Rocking of the arm 429 in the counter-clockwise direction as seen in Fig. 18 thereby takes place through the rod 416.

On the yoke 429, which is automatically shifted at every change of the totalizer content into negative or positive, there is mounted a lower arm 436 which has an opening for a rod 496. The rod 496 is pivoted to the pin 467 of the lever 468 in such a manner that it can effect a small movement at right angles to the plane of the paper in Fig. 1, when the lower arm 436 of the yoke 429 rocks about the rod 423.

The yoke 429, the position of which is always dependent upon the character of the amount in the totalizer, and the slide 487, the setting of which is always dependent upon the addition or subtraction position of the totalizer, are disposed in operative connection with the rod 496 in the following manner.

The slide 487, as shown in Figs. 2 to 5, has two notches 497 and 498 which, under certain conditions, allow the rod 496 to pass through. In Fig. 2 the slide 487 is in its lower or addition position, and the arm 436, which is schematically represented by a dash and dot line, is in the forward position corresponding to a positive amount in the totalizer. In this case the right-hand end (Fig. 1) of the rod 496 lies opposite the notch 497. This makes possible a right-hand movement of the rod 496 when the totalizer is in position for addition and indicates a positive amount. If now, for example, by actuating the total key 454, the rod 462 is moved to the right in Fig. 1, then the spring 470 turns the lever 468 in the clockwise direction and the rod 496 engaging the pin 467 is pushed through the notch 497. Simultaneously a rod 499 is actuated against the action of a spring 503 which rod is connected by a joint pin 500 to the lever 468, and is guided by means of the slot 501 and a pin 502.

The rod 499 has a pin 504 which operates to move a pawl 505 pivoted on a pin 510 on a slide 75

509, against the action of a spring 506 whereby this pawl is turned to bring its tooth out of the path of a locking plate 507. This enables the slide 509 under the action of a spring 508 to move to the right in Fig. 1 as soon as its stop 511 bearing against a pin 141 on the drive disk 142 is moved at the beginning of the rotation of the disk 142 in the direction of the arrow 143. The movement of the slide 509 causes a lever 513 to rock about a pin 550. This lever 513 bears against a control rod 514 having arms 515 which can rock on the pivot 550 of the zero levers. During right-hand movement of the slide 509 there takes place a left-hand movement of the rod 514, which by means of the lugs 516 rotates all of the zero levers 452 out of the path of the bars 453. Hereby the step bars 453 can perform their movement as required for a total-taking operation. At the end of the return movement the zero levers 452 are rocked into operative position by the pin 141 against the action of the spring 508.

The rod 499 serves the further purpose of controlling the engaging movement of the totalizer during forward operation of the machine. For this purpose there is provided a pin 517 which, according to Fig. 6, by its left-hand movement, permits clockwise rotation of a pawl 136 under the influence of a spring 146. The pawl 136 which is mounted on a pin 518 on a shift member 130, carries its contact surface 181 into the path of the drive pin 141 and is thereby carried along with the shift member 130 to the right at the beginning of the machine operation. By this movement of the shift member 130 to the right, Fig. 7, the totalizer 317 is engaged as follows: A link 902 is jointed to the shift member 130 by a pin 901, Fig. 18, the other end of which link engages a pin 903 of a crank 904 which is fast on the shaft 764. In its right-hand movement the shift member 130 rocks the shaft 764 in counter-clockwise direction, Fig. 18, by means of the lever 902 and the crank 904 and the cam disk 763 fixed on the shaft 764 acts through the groove 761 to bring the totalizer 317, as already described, into engagement with the rack sectors 3.

Furthermore, the rod 499, according to Fig. 1, has a pin 564 which cooperates in its left-hand movement with the upper surface 565 of a lever 558 pivoted at 502 and having a hump 561 bearing under the action of a spring 559 against a pin 560 on the bell-crank 456. The lever 558 has a tooth 562 which can engage the joint pin 563, when by actuation of a total key the pin 560 of the bell-crank 456 moves to the left in Fig. 1. This locking of the joint pin 563 by the tooth 562 produces the result that the lever 523 cannot move under the action of the spring 524, and the locking takes place when a total key is depressed and the rod 499 is in the illustrated position of rest. The locking, however, is prevented by the left-hand movement of the rod 499 and the encounter of the pin 564 with the surface 565. On release of the locking, the slide 522 jointed to the joint pin 563, which slide is guided on a pin 521, follows the movement of the drive pin 141 with its right-hand contact surface until the spring 524 brings it into contact, at the left-hand end of its slot 525, with the pin 521. This movement is sufficient to bring a pin 526 on a lever 528 connected by a spring 527 to the lever 523 behind a pawl 529 tensioned by a spring 568. In this position the parts remain until the drive pin 141 in its backward

movement encounters the slide 522 and rocks the lever 523 in such a manner that the pin 526 carries the pawl 529 along with it. Since this pawl is mounted on a lever 530 and by contact against the pin 531 can move only along with the lever 530 attached to the shaft 532, the shaft 532 also executes a counter-clockwise rotation whereby its lug 533 engaging notches 534 in the key-locking bars 535, 451, shifts the latter to enable the depressed digit keys again to spring up. This release of the digit keys is thus possible only on actuation of a total key, when the rod 499 has effected a left-hand movement; it is prevented when the rod 499 has not moved to the left, for a cause which will be hereinafter explained.

In the rod 499 there is provided a further notch 546 into which can fall a pawl 544 pivoted on a pin 521, under the action of a spring 545, when the rod 499 is in rest position and the pin 141 during its movement in the direction of the arrow 143, permits the pawl 544 to drop in this manner. Disengagement of the pawl 544 is effected at the end of the backward stroke, by means of the drive pin 141.

The backward movement of the rod 499, after any left-hand movement, takes place subsequent to the release of the keys by a spring 503.

When the amount in the totalizer is of positive character and the totalizer is in addition position, substantially the following control movements are effected by the total-taking mechanism. The rod 462, by means of its pawl 472, couples the drive motor by rotating the shaft 475 in the above described manner, and the rod 499 rocks pawl 505 to cause disengagement of zero levers 452 upon rearward movement of pin 141 and also rocks the total pawl 136, to engage the totalizer.

Also any depressed total key 454 or 455 is again released at the end of the machine operation, and the total-taking mechanism is again restored to normal. Furthermore, in its rocking movement the drive pin 140 encounters an arm 559 of a bell-crank 536 which by means of a pin 537 turns a pawl 472 in a counter-clockwise direction, thereby enabling the motor coupling lever 474 to return to its initial position.

In the case of sub-total taking, the key stem 455 operates directly upon the bell-crank 456 and the upper pawls 135 and 137 (Fig. 6), which are mounted on pins 519 and 520 of the shift member 130, are not shifted by the sub-total key. The return movement of the shift member 130 for disengaging the totalizer is effected, when at the end of its return stroke the drive pin 141 encounters the surface 138 of the shift member 130.

The key 454, by which the machine is set for a final total, in the machine illustrated operates not only on the bell-crank 456 to actuate the above-described total-taking mechanism according to Fig. 6, but also upon a transmission lever 538. This lever is pivoted at 539 and by means of a pin 540 it can bring the pawl 137 against the action of its spring 147 into the path of the drive pin 140, whereby the shift member 130, which was moved at the beginning of the forward stroke to the right by the parts 141, 136, is returned again to the left at the end of the forward stroke, as is necessary to disengage the totalizer when the final total is taken. The lever 538 has another pin 541 at its outer end, engaging a fork of a lever 542. On depressing the total key 454, this lever 542 is turned in such

5 a manner that its lower surface engages a pin 543 on the pawl 135. By these means the pawl 135 is brought out of the path of the drive pin 140, whereby the latter at the beginning of the return stroke cannot shift the shift member back to the right and thereby again render the totalizer operative, which would be undesirable, Fig. 1d.

10 On the pin 463 connecting the rod 462 with the bell-crank 464, there is jointed a further rod 547 in such a manner that this rod 547 can also effect a small movement at right angles to the plane of the drawings. This left-hand end of the rod 547 is provided with a bend 548 in which is fixed a pin 549. By this pin 549 the rod 547 is slidably guided in an opening of the arm 436 and thus performs also the movements of the arm 436 during the change of the character of the amount in the totalizer. The rod 547 has a notch 553 in which can engage a pin 551 when the arm 436 and the rod 547 assume their position adjacent the side wall 490 with a negative amount in the totalizer (Figs. 4 and 5). In this case, by means of the right-hand movement of the rod 547 upon depression of a total key, the pin 551 of a lever 333 can be moved to the right through the left end of the notch 553, whereby the left-hand movement of the rod 326 positions the totalizer 317 for subtraction. If the amount in the totalizer is positive, a shifting of the pin 551 and of the lever 333 by a total key is not necessary because in the machine illustrated the totalizer is always automatically shifted to addition. If the amount is positive, the rod 547 is rocked by the arm 436 so far away from the side wall 490 that the pin 551 cannot engage in the notch 553. The notch 553 is extended so far towards the right that lever 333, even without movement of the total-taking mechanism, can effect its rocking movement. This is necessary, for example, when the totalizer 317 is shifted to subtraction position by means of a carriage projection 328, a horizontally extending double-armed lever 329, a tension wire 330, a bell-crank 331, and a rod 332.

30 In Fig. 7 the shift member 130 carries a further pin 570. Against this there bears an edge of a disk 571 rotatable about a pin 572 in the side wall 490. On the disk 571 there is fixed a pin 573 which bears on the rod 557. On total-taking, the shift member 130 moves to the right during the forward stroke of the machine, whereby the pin 570 rocks the disk 571 in the counter-clockwise direction. Hereby the rod 557 is moved upwardly by the pin 573 to such an extent and at such an instant that the drive pin 140 cannot engage the hook 552. This reliably prevents any changeover of the totalizer during total-taking in which the armature 130 moves to the right during the forward stroke.

35 A negative amount in and subtraction position of the totalizer result in rear position of the arm 436 adjacent the side wall 490 and upper position of the slide 487. In this case, according to Fig. 5, the rod 536 lies in front of the opening 498. On actuation of a total key 454 or 455, the rod 462 with the pawl 472 is moved to the right to couple the drive motor and the spring 470 pushes the rod 496 through the opening 498, setting the machine for performing a total-taking operation in the above-described manner, by means of the rod 499. Moreover, the pin 551, which at this time engages the notch 553, is carried along so that the pin 327 is brought to the left. This movement, however, has no result

because the totalizer 317 is already set for subtraction.

If the totalizer content is negative and the totalizer is positioned for addition, the arm 436 assumes its lower position adjacent the wall 490 and the slide 487 its lower position, as shown in Fig. 4. In this case, neither of the openings 497 and 498 is in position for a right-hand movement of the rod 496, in Fig. 1. On actuation of a total key 454 or 455 and right-hand movement of the rod 462, the lever 468 cannot be carried along by the spring 470, because the rod 496 jointed to the pin 467 prevents this. In this case, also the rod 499 cannot at once move to the left, but as soon as the drive pin 141 begins its movement, the rod 499 is locked by dropping of the pawl 544 into the notch 546, until the drive pin 141 towards the end of its return stroke again releases the pawl 544. Also, the pawl 558, after its release by the pin 560, has engaged behind the joint pin 563 in order to prevent release of the depressed total key at the end of the machine operation. Furthermore, the pin 504 cannot release the zero levers 452. Since, however, the pin 551 is in the notch 553, the lever 333 is moved in order to prepare the totalizer 317, which is in addition position, for its subtraction position. The connection of the drive motor by means of the pawl 472 on the rod 462 is now effected and the operation is as follows:

The drive motor gives the main shaft 1 a rocking movement, first in the direction of the arrow 143 and then reversely. In this action, the drive pin 140 (Fig. 7) engages the hook 552 and shifts the totalizer 317 from addition to subtraction position. The drive pin 140 also imparts a clockwise rotation to the lever 536 through its cammed arm 569. Hereby, by means of the pin 537, the pawl 472 receives a counter-clockwise rotation, bringing said pawl out of engagement with the pin 473, which allows a restoration of the motor-coupling lever 474 into its initial position under the action of a spring. In its disengaged position, the pawl 472 is moved to the right and held idly under the pull of its spring 571 against the pin 473. In the uncoupling movement, a second pawl 566 is swung slightly in clockwise direction, which pawl is pivoted at 467 to the rod 468. Upon return of the pin 537, the lever 566, owing to its spring 567, again follows the pin 537 until it again comes below the pin 473. During the shift of the totalizer to subtraction, the slide 487 reaches its upper position. The position of the rod 496 relatively to the slide is as shown in Fig. 5. Nevertheless, the rod 496 at first cannot pass through the opening 498, being prevented from this because the pawl 544 still holds the rod 499 locked. It is only afterwards, at the end of the machine operation, when the drive pin 141 has lifted the pawl 544 out of the notch 546, that the rod 499 can move to the left and the rod 496 can move to the right through the opening 498. During this movement, by means of the pawl 566, the pin 473 is carried along, and by means of the motor-coupling lever 474 the drive motor is coupled for an immediately following machine operation. The left-hand movement of the rod 499 takes place in similar manner as above described and serves the purpose of raising the zero levers 452, engaging the total-taking pawl 136, releasing the keys 454, 455 at the end of the working operation, and restoring to normal the other shifted parts.

When the totalizer has a positive content and is in subtraction position, the arm 436 is in its forward position and the slide 487 is in its upper position, as shown in Fig. 3. In this case, the pin 551 is out of register with the notch 553 and the slide 487 at first also prevents passage of the rod 496. This time, upon depression of a total key, there takes place only a movement of the rod 462 and of the pawl 472 to the right, while the spring 470 is tensioned and the parts 496, 468, 499 are again locked first by the slide 487 and then by the pawl 544 until the end of the first machine operation. The shifting of the totalizer into addition position takes place automatically by the spring 335 without operation of the lever 333 or the pin 551. During the machine operation, the pawl 472 is disengaged by the parts 140, 536, 537 in order that when the parts 499, 468, 496 are released at the end of the machine operation upon downward movement of the slide 487 and release of the pawl 544, the pawl 566 shall again engage the pin 473 and couple the motor, by means of the lever 474, for a second machine operation. In this machine operation, with raising of the zero levers 452, engagement of the total-taking pawl 136, release of the total key, and restoration of the other shifted parts, the correct positive total is taken from the totalizer which was shifted to addition in the preceding idle stroke.

A tension rod 465 is jointed to the bell-crank 464 attached by joint pin 463 to the rod 462, which rod 465 is connected with a double-armed lever 466 pivoted on a shaft 349. This lever 466 has 35 stops 467 cooperating with the paper carriage 10 whereby the rod 462 can also be operated for total-taking automatically from the paper carriage. The rods 460, 458, 456 do not participate in this movement, and the pin 560 remains standing above the lever 558. With this automatic totalizing no key release is necessary. Furthermore, the rod 499 is operated in the above-described manner.

The total control mechanism just described only sets the lower pawl 136, and not the pawls 135, 137, by means of the rod 499, being a subtotal control. When final totals are to be taken, a second rod mechanism 713, 542, 538 is used which is associated with the upper pawls 135 and 137, and, for example, may be connected to the lever 464. When connected to the lever 464, separate mechanism is necessary for the automatic setting of the totalizer to non-addition. This is avoided in the herein-illustrated construction, in which the rod 713 leads to a separate bell-crank 574, which can be controlled from the paper carriage in similar manner as the above-described bell-cranks 331, 464. When this bell-crank 574 alone is actuated, it sets up the non-addition position of the shift member 130 and of the associated totalizer by disengaging the pawl 135. If, however, it is actuated together with a subtotal rod mechanism 464, 465, then the machine is set for taking a correct final total, since the pawls 136 and 137 are then engaged and the pawl 135 disengaged. The pawls 135 and 137 can also be moved by a non-add key 633.

The invention is particularly advantageous when the machine is operated automatically. By arranging control members on the paper carriage in desired bookkeeping columns and without manipulation of keys, correct totals can be printed. The field of utility of the invention can be further enlarged by the mechanism now to be described.

On an arm 573 (Fig. 1) of the yoke 429, there is arranged a further rod 217 (Fig. 8) which has a slotted end for moving a lever 218, in dependency upon the presence of a positive or negative content of the totalizer, towards or away from the side wall 490. The rod 217 is movable by means of a lever 212 and a tension wire 216 from a paper carriage stop 281, to the right in Fig. 8. In this movement, by means of an end 214 of a notch in the rod 217, it can draw a pin 215 on a lever 218 to the right. If, however, the rod 217, for example, when the totalizer content is negative, is swung out of the plane of the notch 214 by the arm 573, then the movement of the rod 217 is idle. This device serves for skipping column spaces in dependency upon the character of the content of the totalizer and works in the following manner:

A skip key 170 operates through a pin 176 on the parts 171, 172 and draws the lever 179 to the left against the spring 182 so that a locking lever 184 under the action of the spring 183 comes to lie behind a pin 185. Hereby a pin 186 is released and the spring 186 moves a lever 188, 185 counter-clockwise. In this movement, a locking pawl 191 pivoted on the pin 186 brings its lug under a pin 183 on the lever 184. The position of the lug under the pin 183 is so determined that a counter-clockwise rotation of a latch member 38, which serves together with the part 31 for arresting the paper carriage 10 by means of adjustable stops 28, cannot lift the pin 183. Such a counter-clockwise rotation of the latch member 38, in which this comes out of the engagement with its opposing stop 28, produces only a short rotation of the lever 185, 186, until the latch member 38 has passed the right-hand end of the lever 185. The lever 185 then flies back and its upper end prevents the latch member from return movement, which is effected by spring power. When a control member 381 comes into the path of a lever 362, the pull rod 216 moves the rod 217 in the above-mentioned manner, without being able to carry along the pin 215 when the totalizer content is negative. With a positive content in the totalizer, however, when the notch 214 in the rod 217 is in the plane of the pin 215, the control member 381 effects a stopping of the paper carriage. The movement of the pin 215 is sufficient that the locking lever 181 raises the pin 183 and the restoration of the key 170 can take place by means of the spring 182. With a negative content in the totalizer, the carriage 10 travels a little further until a control member 282 encounters a lever 186 and the pin 281 rotates the lever 185 through parts 187, 188 by a large angular amount, causing both the latch member 38 and the skip key 170 to return to initial position.

The engagement of the drive motor 184 to effect a machine operation takes place by means of the lever 171 or by means of an extension 577 of the stem of the skip key 170. The extension 577 engages a pin 578 which actuates the yoke 579 mounted on the shaft 678 shown in Fig. 30. The yoke 579 rocks in clockwise direction and causes the lever 678 to engage the coupling and to close the motor circuit. The engagement of the coupling and the closing of the circuit is effected in similar manner as by means of the shaft 475 due to shifting of the lever 474. On the pin 578 there also operates an extension 580 of the motor key 581 which produces a column spacing movement of the carriage.

Furthermore, a downward extension of the 75

yoke 579 may be connected with a rod 582 which moves to the left upon actuation of one of the motor keys 170 or 581 and thereby actuates a toggle lever 583, 584 and a bell-crank 377 about the pin 312. This causes a slide 384, Fig. 25, which is movable on a disk 64 by means of a spring 385 and a slot-and-pin guide 383, 381, and 382, 386, to be released in such a manner that it can come under a roller 386 during a clockwise rotation effected by the main drive shaft 1 and transmitted by means of rods 60, 61, 62 to the shaft 63, and in the return counter-clockwise movement said shaft drives a disk 387 as described in the prior patent application Serial No. 39,065 of Ewald. By this rotation of the disk 387, a rotary movement is produced of a shaft 38 which, in its counter-clockwise rotation, by means of teeth 388, 389, can bring the stop 31 out of the path of the opposing stop 28, in order to release a carriage skip movement under the action of a spring (not shown).

The lever 468 shown in Fig. 1 is connected with this mechanism. According to Fig. 9, a slide 585 is mounted on the lever 468, guided by means of slots 586, 587 and pins 469, 467. On the lever 468 are provided two depressions 588, 589 in which can engage a spring detent 590 during shifting of the slide 585 alternately upwards and downwards. The lower end of the slide cooperates with a pin 591 on the rod 582.

It is hereby obtained that after termination of a total-taking operation the paper carriage can automatically skip to the next space, in which the slide 585 shifts the slide 384 to the right, Fig. 9. Hereby the same action takes place as on release of the slide 384 by the bell-crank 377. The slide 585 during the aforesaid shifting of the slide 384 has to overcome the resistance of the spring 385, which tends to draw the lever 582 to the right, Fig. 9. A slot 627 in the left-hand end of the rod 582 prevents a repeated switching in of the motor by the yoke 579, which regularly takes place in a total-taking operation by means of the rod 462 and the pawl 586 as previously described.

The key 587 switches in the motor 704 for which purpose it has a pin 588 which rocks a lever 589 anti-clockwise. This lever 589 has a pawl 680 which acts on the pin 473 and by means of the lever 474 rotates the motor engaging shaft 475 in the above described manner.

In automatic line advance and automatic release of a carriage jump, it is essential that the slide 585 shall not be mounted on such parts as are operated in an idle stroke, but on one of the parts which perform their operative movement only in taking the correct positive or negative total of the totalizer.

This application relates to improvements in the machine described in the co-pending application Serial No. 39,065, Ewald, filed September 3, 1935.

We claim:

1. In a calculating machine the combination of a machine drive, a differential mechanism, an adding and subtracting totalizer, a change-over means for shifting the totalizer from its addition position to its subtraction position or vice versa, transmission members for actuating the change-over means from the machine drive, control means between the transmission members and the change-over means controlling the shifting of the totalizer, a shiftable member for engaging the totalizer with the differential mechanism, controllable members for connecting the

shiftable member with the machine drive for a total-taking operation, intermediate members for shifting one of the controllable members into operative position, settable members for operating the intermediate members, yielding means between the settable members and the intermediate members, first means connected to the settable members for initiating the machine drive, second means connected to the intermediate members for initiating the machine drive, and locking means for locking the intermediate members, said locking means being controlled in dependence upon the position of the totalizer and upon the positive or negative sign of the contents of the totalizer and being operative in positions of the totalizer not corresponding to the sign of its contents.

2. In a calculating machine according to claim

1, in which the settable members comprise a total key, and in which is provided a member for latching the total key in its depressed position, means for releasing said latching member, means for engaging said releasing means, a pass-by pawl pivotally connected to the engaging means, means coacting with the pass-by pawl and being coupled with the machine drive in such a manner that it engages the pass-by pawl at the end of a machine operation, means for locking the said coacting means in its inoperative position, and control means for making inoperative said locking means and connected to the intermediate members, said control means becoming effective when the second initiating means becomes effective.

HEINRICH KONRAD FRIEDRICH EWALD.
